(57) **CLAIM**

The ornamental design for a combination collar and leash, as shown and described.

DESCRIPTION

FIG. 1 is a top perspective view of a combination collar and leash, showing a first embodiment of my new design, shown in a condition of use;

FIG. 2 is a top, front, left perspective view of the combination collar and leash of FIG. 1;

FIG. 3 is a rear elevational view thereof;

FIG. 4 is a front elevational view thereof;

FIG. 5 is a top plan view thereof;

FIG. 6 is a bottom plan view thereof;

FIG. 7 is a left side elevation view thereof, the right side elevation view being a mirror image thereof;

FIG. 8 is a top perspective view of a second embodiment of a combination collar and leash, shown in a condition of use;

FIG. 9 is a top, front, left perspective view of the combination collar and leash of FIG. 8;

FIG. 10 is a rear elevation view thereof;

FIG. 11 is a front elevation view thereof;

FIG. 12 is a top plan view thereof;

FIG. 13 is a bottom plan view thereof;

FIG. 14 is a left side elevation view thereof, the right side elevation view being a mirror image thereof.

The equal-length broken lines on the claimed portion of the combination collar and leash depict stitching and form part of the claimed design. The equal-length broken lines that show a pet in FIGS. 1 and 8 depict environmental matter form no part of the claimed design. The dash-dot-dash broken lines define the boundaries of the claimed design. The equal-length broken lines within the areas defined by the boundaries form no part of the claimed design.
